MINING MACHINE AND AUTOMATIC CYCLING CONTROL MECHANISM THEREFOR

Arthur L. Barrett, Franklin, Pa., assignor to Joy Manufacturing Company, Pittsburgh, Pa., a corporation of Pennsylvania

Application December 18, 1950, Serial No. 201,411

49 Claims. (Cl. 262—29)

This invention relates to a continuous mining machine, and especially to a continuous mining machine which is substantially automatic in its operation.

Continuous mining machines of the type disclosed in commonly owned patent applications Serial Nos. 102,995 and 102,996 of John D. Russell and John R. Sibley, respectively, and both filed July 5, 1949, provide a considerable advantage over older and more conventional methods of mining in that they eliminate the dangers which go along with blasting, and substantially increase the tonnage per man-shift. A further improvement could be effected by providing means to operate such a machine, or at least a substantial portion of its operating cycle, automatically.

It is, accordingly, an object of this invention to provide a continuous mining machine which is substantially automatic in its operation. The particular and specific embodiment of the continuous mining machine shown is one in which a vein-attacking and disintegrating instrument is mounted for a plurality of movements in a coal face. The above and other objects are achieved in the embodiment of the machine shown by limit means positioned to be actuated as each separate operation of the cycle nears completion, thus initiating the next succeeding operation. The limit means referred to may be hydraulic or electric, and may operate with hydraulic or electric mechanism.

In the drawings:

Fig. 1 is a top plan view of the forward end of a mining machine of the type referred to above, showing the vein-attacking and disintegrating instrument and immediately associated mechanism.

Fig. 2 is a side elevation view of substantially that portion of the machine shown in Fig. 1.

Fig. 3 is a view in section on a substantially horizontal plane, showing some details of the machine, and being on a larger scale than Figs. 1 and 2.

Fig. 4 is a schematic view of a hydraulic automatic mechanism for a mining machine of the type shown in Figs. 1-3.

Fig. 5 is a detail view, being a view partially in section of the slave cylinder and the operating cylinder for the selector valve and being on a larger scale than Fig. 4.

Fig. 6 is another detail view, again being a partial sectional view showing the one-way drive mechanism for the selector valve, and being on a larger scale than Fig. 4.

Fig. 7 is a detail view, on an enlarged scale, showing the mechanism for holding the selector valve in an operating position.

Fig. 8 is an enlarged view in section through the selector valve to show internal construction, and showing the selector valve in position for the sumping-in operation.

Fig. 9 is a view similar to Fig. 8, but showing the valve in position for the upswing operation.

Fig. 10 is a view similar to Fig. 8, but showing the valve in position for the retract operation.

2

Fig. 11 is another view similar to Fig. 8 but showing the valve in position for the lowering or downswing operation.

Fig. 12 is a view in section substantially on line 12—12 of Fig. 9.

Fig. 13 is a view in section substantially on line 13—13 of Fig. 11.

Fig. 14 is a view in section on line 14—14 of Fig. 12.

Fig. 15 is a schematic view of another embodiment of mechanism for making the mining machine automatic.

Fig. 16 is a third embodiment of the invention showing a schematic view of still another automatic mechanism.

Fig. 17 is a schematic view of a fourth embodiment of the invention.

Fig. 18 is a schematic view of a fifth embodiment of the invention.

Fig. 19 is an operational view, showing a horizontal section through a portion of a mine, in which the mining machine is seen in plan.

Fig. 20 is a section on a vertical plane showing the mining machine of Fig. 19 in side elevation.

The forward end of a mining machine of the type described is shown in Figs. 1 and 2. The machine comprises a mobile base mounted on a caterpillar track 2, a vein-attacking and disintegrating instrument 4, which is mounted for swinging in vertical planes about a horizontal axis shown at 6 of Fig. 2, the axis being the axis of the shaft carrying the drive sprockets for the chains of the vein-attacking and disintegrating instrument 4. This shaft is not shown in detail here, but can be seen readily by reference to the above-identified application Serial No. 102,996. The vein-attacking and disintegrating instrument is mounted for sliding or rectilinear movement on a sliding frame or support 8 which reciprocates on and relative to a horizontal supporting frame or turntable 10. The turntable frame 10 is swingable in a horizontal plane about a vertical axis, which vertical axis is substantially the center of arcuate members 12 and 14 of the turntable frame 10. It may be pointed out again that not all of the details of the machine are shown in this application, but can be seen by reference to the above-identified Sibley application Ser. No. 102,996.

The above-referred-to rectilinear movement of the vein-attacking and disintegrating instrument 4 provides the sumping-in and retracting movement. The rectilinear movement is provided by the sump cylinders 16. Swinging of the instrument 4 in vertical planes is accomplished by means of the upswing cylinders 18. Swinging of the turntable frame 10, and with it the instrument 4, in a horizontal plane is accomplished by means of the swinging cylinders 20. As will readily be understood by reference to the above-identified Sibley application, the cylinders 20 carry pistons having piston rods which are anchored to a stationary portion of the machine frame. To the exterior of the cylinders 20 there is secured a pair of sheaves 22 around which are wrapped chains 24. Chains 24 are secured at one end to the stationary frame by means of a resilient shock absorbing mechanism indicated generally at 26. The chains wrap around other sheaves 28 and 30, and at their other ends are secured at 32 to the swingable frame 10.

In the schematic views (Figs. 4 and 15-18), the two sump cylinders are represented by a single sump cylinder 16, the two upswing cylinders are represented by a single cylinder 18, and the two horizontal swing cylinders are represented by a single cylinder 20.

The hydraulic automatic system

Reference will now be had to Figs. 4-14 for a detailed consideration of the hydraulic automatic mecha-

nism. A tank or reservoir 34 is provided with a supply of hydraulic fluid. A hydraulic pump 36 of any satisfactory design, driven by any desirable power source (not shown) is connected with the reservoir by a conduit 38 and discharges into a discharge line 40. The line or conduit 40 connects the pump 36 with selector means, such as valve 42.

There is provided in the pump discharge line 40 a manually operable valve 44. A by-pass line or conduit 46 connects one port of valve 44 with the pump discharge conduit 40 and is adapted to connect through the valve 44 to reservoir 34 by way of a by-pass conduit 48. The valve 44 will preferably be a conventional three-position, manually operable valve, having one position in which all fluid flow is cut off, another position in which fluid flow through the pump discharge line 40 is permitted, and another position in which hydraulic fluid under pressure is by-passed back to the reservoir by way of conduits 46 and 48. Valves of the type indicated at 44 are stock items which are readily available, so it is not necessary to describe valve 44 in detail.

The selector valve 42 is, in effect, a distributor valve and is provided with a conduit 50 connecting the valve 42 with the tank or reservoir 34, a conduit 52 connecting valve 42 with one end of the sump cylinder 16, a conduit 54 connecting the valve 42 with the other end of the sump cylinder 16, and a conduit 56 connecting the valve 42 with the upswing cylinder 18.

It will, of course, be understood by those skilled in the art that the single cylinders 16, 18, and 20, shown in the schematic views, are merely representative of the hydraulic motive power shown in Figs. 1-3.

The selector valve 42 and its associated operating mechanism are more generally described as selector means, having a given orientation for each operation of the vein-attacking and disintegrating instrument 4. More specifically, the valve 42, shown in Fig. 4, is a master selector which has a given operating position for each operation of the instrument 4, and which is movable into those operating positions in a certain sequence by means which are shown in detail in Figs. 4-14 and which will now be described.

Sump cylinder 16 is, in effect, a hydraulic motor having a piston rod or drive member 60 (see also Fig. 3) connected to the sliding frame 8 to effect the rectilinear movement referred to above. Similarly, upswing cylinder 18 is a hydraulic motor having a piston rod or drive member 62 connected to effect the swinging movement in vertical planes referred to above. Limit means 64, 66, 68, 70 and 72 are provided to be engaged by some portion of the moving parts of the machine near the ends of the various operations of the operating cycle. It will, of course, be understood by those skilled in the art that the limit means may be disposed in any convenient location for actuation by any suitable portion or portions of the machine. However, for the sake of convenience, the limit means are herein shown schematically as being engaged by arms or projections attached to the piston rods 60 and 62. More specifically, an arm or projection 74 on the rod 60 is in position to actuate limit means 64 and 70; an arm or projection 76 on piston rod 62 is in position to actuate limit means 66 and 68; and an arm or projection 78 is also carried by piston rod 60 in such a manner as to actuate the limit means 72.

The limit means are simply cylinders with pistons reciprocable therein, the piston rods extending out through the cylinders at one end in position to be actuated by one of the projections 74, 76 or 78. The end of each cylinder opposite the piston rod end is connected with conduit 80, and conduit 80 connects with a cylinder 82 (Figs. 4 and 5). Cylinder 82 is provided with a bore 84 in which reciprocates a floating piston 86. Piston 86 is provided with a skirt 88 which serves as a control valve for the means which changes the orientation of the master selector 42. More specifically, the skirt 88 is provided with

a peripheral groove 90 which in one position registers with conduits 92 and 94 and in another position registers with conduits 96 and 98. Conduits 92 and 96 both connect with a conduit 100 which connects with a fluid motor 102.

Piston 86 is preferably hollow to receive a spring 104. The spring 104 is in compression, one end resting against the piston 86 and the other end resting against the opposite end wall of cylinder 82. Spring 104 biases the piston 86 into an operating position in which conduit 92 communicates with conduit 94 by way of groove 90. When piston 86 is pushed to the extreme right limit of its travel by the provision of fluid pressure through conduit 80, groove 90 is in position to communicate conduits 96 and 98.

A hydraulic accumulator 106 of the type disclosed in Mercier Patent No. 2,256,835, reissued December 4, 1951, No. Re. 23,437, is connected with the pump discharge line 40 by a check valve 108 and a conduit 110. The aforesaid conduit 98 is connected with conduit 110 in order to receive fluid from the accumulator 106. It may be pointed out here that in many applications it may be desirable to dispense with the accumulator, in which case the conduit 98 will be connected directly with the pump discharge conduit 40. Conduit 94 is a hydraulic fluid exhaust line which connects with the tank 34 by way of exhaust line or conduit 50.

A manually operable valve 112 is provided, being connected with the conduit 100 by a conduit 114 and a branch conduit 116, and connecting with conduit 94 by a conduit 118 and with conduit 98 by a conduit 120. The valve 112 is preferably a three-way valve having one operating position in which no fluid flow is permitted through the valve; a second operating position in which fluid flows from conduit 120 to conduit 114 by way of branch conduit 116; and a third operating position in which fluid flow is permitted from conduit 114 to the tank 34 by way of conduits 118, 94, and 50.

Each of the limit means 64, 66, 68, and 70 constitutes, in effect, a master cylinder which controls the operation of the slave cylinder 82. A reservoir 122 is connected with the conduit 80 through a check valve 124 and a relief valve 126. The check valve 124 insures that the hydraulic system comprising the conduit 80 and its connected cylinders shall always be full of hydraulic fluid, and relief valve 126 insures against excessive pressures building up in the system for one reason or another, as for example, in the event that one of the limit means should stick instead of returning to its neutral position.

Reference is now had to the fluid motor 102 and to its drive connection with the valve 42, best shown in Figs. 5-7. Fluid motor 102 is preferably a hydraulic cylinder in which a piston 128 is reciprocable. Piston 128 is biased leftward as seen in Fig. 5 by a spring 130. A stepped piston rod 132 provides a driving connection between piston 128 and a rack 134. A pinion 136 meshes with the rack 134.

Pinion 136 has a one-way drive connection with the rotatable valve body shaft 138 of valve 42. If desired, this one-way drive may be provided by means of a ratchet and pawl mechanism, but a preferred form of drive is that shown in Fig. 6. Gear or pinion 136 is provided with a plurality of pockets or recesses 140. In each recess 140 a ball 142 is located. Balls 142 engage slightly curved surfaces 144 on the shaft 138. The surfaces 144 may, if desired, be plane, but are shown in Fig. 6 as curved surfaces having a relatively long radius. Recesses 140 are provided with surfaces 146 which are struck from the same centers as the surfaces 144. The surfaces 146 are bounded at one end by spherical surfaces having substantially the curvature of the balls 142, and at their opposite ends intersect with other surfaces 148 which are curved and are struck from the center of the pinion 136 (which is also, of course, the center of the shaft 138). The surfaces 148 are also bounded by

spherical surfaces having the same curvature as the balls 142. The surfaces 150 are struck from the center of the pinion 136 and provide for clearance of the corners of the nearly square portion of shaft 138.

In order to insure a precise positioning or orientation of valve 42 for each operation of the cycle, a detent mechanism, such as is shown in Fig. 7, may be provided. Fig. 7 shows a squared portion 152 of shaft 138 provided with four recesses 154. The recesses 154 are spherical and have the same curvature as a ball 156 which is held in a recess 158 provided in the housing of valve 42. Ball 156 is spring-biased into an alined recess 154 by means of a spring 160.

Reference will now be had to Figs. 8-14 for a detailed discussion of the selector valve 42. Valve 42 comprises a valve housing 162 having a cylindrical bore 164; an end cover plate 166; an end cover plate 168; and a valve body 170 rotatably disposed in the cylindrical bore 164. The housing 162 is provided with a number of passages: a substantially radial passage 172 and a passage 174 intersecting the passage 172 and connecting at its other end with the conduit 52; a substantially radial passage 176; another passage 178 intersecting with passage 176, still another passage 180 intersecting passage 178 and in communication with conduit 56; a substantially radial passage 182, and another passage 184 intersecting passage 182 and connecting with conduit 54; a substantially radial groove 186 (Fig. 14) intersecting at one end with an arcuate groove 188 and at its other end with a groove 190 which is in communication with conduit 50 to the tank; and a plurality of longitudinal passages 192, 194 and 196 connecting the arcuate groove 188 with the bore 164. The end cover plate 168 is provided with cooperating grooves 188' and 190' which, together with the grooves 188 and 190 respectively, in the housing 162, form complete fluid passages. The end cover plate 166 is provided with an axial passage 198 which is in communication with the pump discharge conduit 40.

The rotatable valve body 170 is also provided with passages: an axial passage 200 which is at its one end always in communication with the aforesaid passage 198, and, intersecting with the other end of passage 200, a radial passage 202 which communicates in turn with the passages 172, 176 and 182; a longitudinal passage 204 which communicates in turn with the longitudinal passages 192, 194 and 196, and a tangential passage 206 which intersects at its one end with the longitudinal passage 204, and at its other end communicates in turn with the passages 172, 176 and 182.

The automatic hydraulic swing means

Reference is now made again to Fig. 4 for a description of the automatic control mechanism for the swing cylinders 29. The aforesaid master cylinder 72 is connected by a conduit 210 with a slave cylinder 212. The slave cylinder 212 will be substantially the same as the slave cylinder 82, so a detailed discussion thereof is not warranted. The hydraulic system of master cylinder 72 and slave cylinder 212 is kept full by a gravity reservoir 214, as will be understood by those skilled in the art, the reservoir 214 being connected with conduit 210 by conduits 216 and 218. The conduit 216 is provided with a relief valve 220 and the conduit 218 is provided with a check valve 222.

Slave cylinder 212 operates a control valve to regulate the supply of fluid under pressure to the swing cylinders 29 in substantially the same manner as slave cylinder 82 operates the control (groove 90, Fig. 5) for the fluid motor 102. To this end, conduit 98 has connected therewith one end of a conduit 224, the other end of which connects with the bore of the cylinder 212. Diametrically opposite the conduit 224 is another conduit 226 which connects with a conduit 228. Conduit 228 connects by way of a conduit 230 with the bore of cylinder 212 in another location, and diametrically opposite the

conduit 230 is another conduit 232 which is connected with the hydraulic fluid discharge line 94.

Conduit 228 connects with a four-way valve 234. A conduit 236 connects valve 234 with the spent hydraulic fluid conduit 94, and conduits 238 and 240 connect with the bore 242 of a cylinder 244. Diametrically opposite the conduits 238 and 240, conduits 246 and 248 respectively also connect with the bore 242. A conduit 250 is tapped into conduit 228 between conduit 226 and valve 234, and connects conduit 228 with the right end (as seen in Fig. 4) of cylinder 244 by way of a conduit 252. A conduit 254, having therein a check valve 256, connects the conduit 252 with the pump discharge line 40. Opposite the conduits 238 and 240, conduits 246 and 248 connect with the opposite ends of the swing cylinders, shown schematically in Fig. 4 as a single swing cylinder 20.

A manually operable valve 258 is connected with conduits 246 and 248 by means of conduits 260 and 262 respectively, and connects with the pump discharge line 40 and tank 34 by means of conduits 264 and 266 respectively. Manually operable valve 258 is a three-position valve which for automatic operation is positioned to prevent fluid flow through its connected conduits, and which has one operating position connecting conduit 260 with conduit 264 and conduit 262 with conduit 266, and another operating position for connecting conduit 260 with conduit 266 and conduit 262 with conduit 264.

A piston 268 is reciprocable in bore 242 of cylinder 244, being biased toward the right by a spring 270. Piston 268 is provided with spaced peripheral grooves 272 and 274, which in one operating position of piston 268 are adapted to connect conduit 238 with conduit 246 and conduit 240 with conduit 248.

A piston rod 276 extends out through one end of cylinder 244 and carries a cam follower 278. Cam follower 278 has a camming surface 280 which is adapted to engage substantially identical cams 282, 284 and 286. The cams are movable with respect to the cam follower by mounting either the cams or the cam follower on a portion of the machine which swings in a horizontal plane and mounting the other element on a portion of the mobile base.

The cam follower 278 is mounted for pivotal movement, enabling it to take positions off center with respect to the piston rod 276 and thus with respect to the cylinder 244. Thus, as will be understood by those skilled in the art, cam follower 278 is pivotally mounted by means of a pin 288 on a head 290. Head 290 has an arcuate surface 292 which cooperates with a mating arcuate surface 294 on the cam follower. In one direction (clockwise, as seen in Fig. 4) the arcuate surface 292 is interrupted by a stop 296 which is adapted to engage an extension 298 on the cam follower 278. Springs, not shown, will be provided and will be connected to hold the cam follower 278 in its centered position shown in Fig. 4.

The cam follower 278 is yieldably, and at the same time rotatably, carried on piston rod 276 by a hollow cylinder 300 threaded at one end and closed by a cooperating threaded member 302. The threaded member 302 has a substantially central opening through which passes piston rod 276. The end of piston rod 276 has a stepped-down diameter to receive a nut 304. Nut 304 holds a collar or washer 306 against the shoulder provided by the larger diameter of piston rod 276. Collar or washer 306 engages one end of a spring 308, the other end of the spring abutting against the bottom of the recess or hollow in cylinder 300. Thus, the cylinder 300 provides a yieldable support for cam follower 278 on piston rod 276 and also allows cam follower 278 to turn on the axis of piston rod 276 in order to allow automatic operation for swinging in either direction.

The electrical system of Fig. 15

Reference is now made to Fig. 15 in which the selector

valve is the same to the extent that the master selector 42 is substantially identical, the difference lying in the means to orient the master selector valve; a further difference in the automatic control means of Fig. 15 over that shown in Fig. 4 lies in the automatic means for swinging the vein-attacking and disintegrating instrument in a horizontal plane.

The orientation-changing means in Fig. 15 includes substantially the same rack-and-pinion device consisting of a rack 134' and a pinion 136'. However, in the embodiment shown in Fig. 15, an electromagnetic device, indicated generally at 310, is connected to reciprocate the rack 134'. More specifically, a coil 312 is connected in a power circuit and when energized moves an armature 314 which is connected to the rack 134'. A spring 316 is connected to return the armature 314 to its de-energized position shown in Fig. 15.

One end of coil 312 is connected to the positive side 317 of a D. C. power source by a conductor 318, and the other end of coil 312 is connected by a conductor 320 with a stationary contact 322 of a set of normally open contacts. The other stationary contact 324 thereof is connected by a conductor 326 and a conductor 328 with the negative side 329 of the D. C. power source. A bridging contact 330 of the set of normally open contacts is adapted to be moved into circuit closing position by a solenoid comprising a coil 332 and an armature 334.

The coil 332 is an element of the control circuit for the automatic system which is responsive to completion of one operation of the machine in order to initiate the next operation. The control circuit includes a plurality of limit switches positioned in any suitable manner and location on the machine such that they will be actuated upon completion of a given operation. In the embodiment shown, the limit switches are illustrated as being in position to be actuated by projections on the piston rods of the upswing and sump cylinders, thus, the piston rod 60 of the sump cylinder and piston rod 62 of the upswing cylinder are adapted to actuate limit switches 364, 366, 368, 370, and 372, by means of a projection 74 on piston rod 60, a projection 76 on piston rod 62, and another projection 78 on piston rod 60.

The coil 332 referred to above is connected with conductor 318 by a conductor 374. The other end of coil 332 is connected to a conductor 376 which in turn connects with two branch conductors 378 and 380. Branch conductor 378 is in electrical contact with stationary contacts 382 and 384 of limit switches 364 and 366 respectively. Branch conductor 380 is connected with stationary contacts 386 and 388 of limit switches 368 and 370 respectively, the connection with contact 388 being by way of another branch conductor 390.

Referring again to limit switch 364, a stationary contact 392 is disposed opposite stationary contact 382, and a bridging contact 394 is adapted to connect the contacts 382 and 392 electrically when switch 364 is actuated. Stationary contact 392 is connected electrically by a conductor 396 with a stationary contact 398 of limit switch 366. Another stationary contact 400 opposite contact 398 is adapted to be electrically connected with contact 398 by a bridging contact 402 when switch 366 is actuated. A conductor 404 electrically connects stationary contact 400 of switch 366 with a stationary contact 406 of switch 368. Opposite contact 406 there is another stationary contact 408, and the two contacts 405 and 408 are adapted to be connected electrically by a bridging contact 410 upon actuation of the limit switch 368. Stationary contact 408 is electrically connected by a conductor 412 with a stationary contact 414 of switch 370, the contact 414 being opposite contact 388, referred to above, of limit switch 370; a bridging contact 416 is positionable to close an electric circuit between stationary contacts 388 and 414.

Referring again to switch 366, a stationary contact 418 is disposed opposite contact 384, and a bridging

contact 420 is positionable to close an electric circuit between them. Stationary contact 418 is electrically connected by way of a conductor 422 with a stationary contact 424 of limit switch 370. In limit switch 370, there is a stationary contact 426 opposite the stationary contact 424, and a bridging contact 428 is positionable upon actuation of the switch to complete an electric circuit between contacts 424 and 426. Stationary contact 426 is connected with one side of a D. C. power source; as shown here, contact 426 is connected with the negative side 329 of the D. C. power source by a conductor 430. As is readily seen by reference to the drawing, the negative side 329 of the line is electrically connected with conductor 404 at 434.

In limit switch 364, there is another stationary contact 436 which is connected with the negative side 329 of the line by a conductor 438. Another stationary contact 440 is in position to be connected electrically with stationary contact 436 by a bridging contact 442. Contact 440 is electrically connected by way of a conductor 444 with a stationary contact 446 of limit switch 368. A bridging contact 448 is positionable to close an electric circuit between stationary contacts 386 and 446.

The automatic electrical swing means

The automatic mechanism for effecting horizontal swinging of the vein-attacking and disintegrating instrument about a vertical axis is accomplished somewhat differently in the embodiment shown in Fig. 15 from the embodiment shown in Fig. 4. In the embodiment shown in Fig. 15, a branch conduit 264 connects the pump discharge conduit 40 with a two-way valve 450. A return line conduit 266 connects the valve 450 with the tank or reservoir 34.

Valve 450 is a simple two-way valve having only two operating positions; namely, open and closed. Valve 450 has two conduits, 452 and 454, connecting with a four-way valve 456. When valve 450 is in its open operating position, conduit 264 is in communication with conduit 454, and conduit 266 is in communication with conduit 452. When valve 450 is in its closed operating position, then of course there is no fluid flow through the valve.

Four-way valve 456 has two additional conduits, 458 and 460, connecting valve 456 with the swing cylinder 20. It will be appreciated by those skilled in the art that valve 456 has two operating positions, in one of which conduit 452 and 458 are connected, and conduits 454 and 460 are connected; and another in which conduits 452 and 460 are connected, and conduits 454 and 458 are connected.

Means are preferably provided to accomplish horizontal swinging manually by bypassing the automatic control valve 450. To this end, a manually operable valve 462 is connected by way of a conduit 464 with the source of fluid supply and by way of the conduit 466 with the tank 34. Conduits 468 and 470 connect the valve 462 with opposite ends of the swing cylinder. As will readily be understood by those skilled in the art, the valve 462 is one which may be any one of a number of valves suitable for the purpose, having three operating positions: one in which conduits 464 and 468 are connected, and conduits 466 and 470 are connected; another in which conduits 464 and 470 are connected, and conduits 466 and 468 are connected; and a third position in which no fluid flow through the valve is permitted.

Valve 450 may be any one of a number of suitable solenoid-operated valves. Power for the operation of valve 450 is supplied through a power circuit which includes a portion of conductor 318 connected with the positive side 317 of a D. C. power source, a conductor 472, the operating coil of valve 450, a conductor 474, a stationary contact 476, a second stationary contact 478, a bridging contact 480 positionable to complete a

circuit between contacts 476 and 478, and a conductor 482 connecting stationary contact 478 with the negative side 329 of the D. C. power source by way of conductor 328.

A control circuit is provided to control the completion and interruption of the power circuit just described. This control circuit includes a coil 484 of a solenoid having an armature 486. One end of coil 484 is connected with the negative side of the D. C. power line by a conductor 488 and the above described conductors 482 and 328. The other end of coil 484 is connected by a conductor 490 with a stationary contact 492. Another stationary contact 494 is disposed opposite contact 492, and a bridging contact 496 is positionable to close an electric circuit between contacts 492 and 494. A conductor 498 connects stationary contact 494 with a stationary contact 500 of limit switch 372. A second stationary contact 502 of limit switch 372 is connected with the positive side 317 of the D. C. power line by a conductor 504. A bridging contact 506 is positionable upon actuation of switch 372 to complete an electric circuit between contacts 500 and 502.

The moving or bridging contact 496 referred to above is mounted to be moved upon horizontal swinging of the vein-attacking and disintegrating instrument about the vertical axis referred to above. To this end, a plurality of stationary cams, some of which are shown at 507, 508, and 510, is in position to be engaged by a cam-follower 512. Cam-follower 512 is connected to effect movement of bridging contact 496 by means of a connecting rod 514.

It can be seen that the cam-follower 512 has a retracted position in which contacts 492, 494, 496 are open, and an extended position in which the contacts 492, 494, 496 are closed.

A circuit is provided in parallel with the circuit comprising contacts 492, 494, 496. This circuit includes a conductor 516 connected with conductor 498, a conductor 518, stationary contacts 520 and 522, a bridging contact 524, and a conductor 526.

Bridging contact 524 is normally closed, and is mounted to be moved into open circuit position by energization of a coil 528 of a solenoid; for this purpose an armature 530 is connected to move bridging contact 524, and is positioned to be moved by coil 528. One end of coil 528 is connected to conductor 516, and the other end of coil 528 is connected with conductor 482 by a conductor 532.

As will be understood by those skilled in the art, the solenoid for coil 528 and contacts 520, 522, 524, is preferably a normally-closed, time-delay-opening solenoid, such as is readily available from a number of commercial sources.

The electrical system of Fig. 16

Reference will now be had to Fig. 16, showing another embodiment of the invention. In this embodiment the limit switches are substantially identical with the limit switches of the embodiment shown in Fig. 15. Accordingly, the limit switches will not be discussed in detail here, but will only be referred to generally by the reference characters 364, 366, 368, 370, and 372, those being the reference characters used in referring to the same limit switches in Fig. 15.

In Fig. 16 the system provides motor means connected to be operated by actuation of the limit switches. As in the embodiment shown in Fig. 15, the selector means is electrically operated and additional motor means are connected to orient the selector means for the several operations of the vein-attacking and disintegrating instrument.

More specifically, the additional motor means is a rotary electric motor having an armature, or rotor, 534 connected to the selector valve 542 by means of a shaft indicated diagrammatically at 544. The motor shown is

a D. C. motor, and the power source shown in the usual D. C. power source available in mining operations, but it will of course be understood by those skilled in the art that alternating current may be used.

5 In the embodiment shown, the motor armature circuit is connected with the positive side 546 of the power source by a conductor 548, and the opposite brush of the motor is connected by a conductor 550 with a stationary contact 552. There is thus a power circuit comprising the positive side 546 of the line, conductor 548, motor 534, conductor 550, the aforesaid stationary contact 552, a second stationary contact 554, a bridging contact 556 positionable to close a circuit between contacts 552 and 554, and a conductor 558 to the negative side 560 of the D. C. power line.

The system provides means to stop motor 534 after rotation through a predetermined arc in order to permit precise positioning of the selector valve 542. This means to stop motor 534 after a predetermined rotation includes the normally-open contacts 552, 554, 556, and electromagnetic means to close the contacts comprising a solenoid having a coil 562 and an armature 564. One end of coil 562 is connected to the conductor 558, and the other end is connected to the positive side of the line through a conductor 566, a stationary contact 568, a bridging contact 570, a stationary contact 572, a conductor 574, conductor 576, through any two of the limit switches 364, 366, 368, 370, and conductor 578.

The contacts 568, 570, and 572, are normally-closed, time-delay-opening contacts of a solenoid having a coil 580, and an armature 582. One end of coil 580 is connected to the conductor 558, and the other end is connected to the conductor 574.

A second limit switch 584 is connected in parallel with the normally closed, time delay-opening, contacts 568, 570, 572. The limit switch 584 comprises a stationary contact 586 and a movable contact 588; the contact 586 is connected with conductor 566 by a conductor 590. Contact 588 is electrically connected with conductor 574 by means of a cam follower 592 on which contact 588 is mounted. The cam follower 592 is shown as being hinged for pivotal movement at its point of connection to conductor 574. The other end of the cam follower 592 is engaged by a cam 594 having a lobe 596. Cam 594 is mounted for rotation by the armature 534, being connected therewith by any suitable means, as for example a shaft shown diagrammatically at 598.

In the preferred embodiment of the form of the invention shown in Fig. 16, still another, third, limit switch indicated generally at 600 is provided in parallel with the limit switches 364, 366, 368, 370. The third-named limit switch 600 comprises a stationary contact 602 and a movable contact 604. Stationary contact 602 is connected with conductor 576 by a conductor 606. Movable contact 604 is electrically connected with conductor 578 by a cam follower 608, on which the contact 604 is mounted.

Cam follower 608 is shown as being hinged at its point of connection to conductor 578, and at its other end rests 60 on a cam 610 having a lobe 612. The cam 610 is likewise rotated by the motor having the armature 534, referred to above, being preferably connected with shaft 598 for such rotation.

65 It will be understood by those skilled in the art that the limit switches 584 and 600 are normally open switches, the lobes of the cams being normally in engagement with their respective cam followers. The cams 594 and 610 are normally rotated through one revolution for each operation in the complete operating cycle of the vein-attacking and disintegrating instrument 4.

The mechanism shown in Fig. 16 to effect horizontal swinging of the instrument 4 about its vertical axis is substantially the same as that shown in Fig. 15 and the description thereof need not be repeated here.

The electrical automatic mechanism shown in Fig. 17

A fourth embodiment of the invention, shown in Fig. 17, likewise is an electrical system, but differs somewhat from the system shown in Figs. 15 and 16. A major difference lies in the different form which the selector means takes, and another major difference lies in the limit switches actuatable by movement of the vein-attacking and disintegrating instrument and their associated electric circuits.

In the embodiment shown in Fig. 17, a reservoir or tank 34 similar to the reservoirs shown in the other systems is provided and supplies hydraulic fluid to a pump 36 through a fluid conduit 38. The pump discharge conduit 40 is shown in Fig. 17 as connecting with branch conduits 614 and 616. Branch conduit 616 has connected with it still another branch conduit 618. Selector means for the embodiment shown in Fig. 17 comprises two valves 620 and 622 shown as being connected with fluid conduits 614 and 618 respectively.

The valves 620 and 622 are shown in Fig. 17 as being connected in parallel with pump 36. This showing is for the purpose of simplifying the schematic diagram illustrating the invention. The valves may in actual practice be thus connected, but they may also be connected in series, as will be understood by those skilled in the art.

Valve 620 has a discharge conduit 624 connecting with tank 34, and valve 622 has a discharge conduit 626 connecting with tank 34. Valve 620 has conduits 628 and 630 connecting with the right and left ends, respectively, of sump cylinders 16. Valve 622 has a single conduit 632 connecting with the upswing cylinders 18.

As will be understood by those skilled in the art, the valves 620 and 622 may be any suitable 4-way, closed center spool, spring centered, double solenoid operated hydraulic valves. Valves of the type referred to are available commercially and need not be detailed here.

The valves 620 and 622 are preferably substantially identical, the second pressure line of valve 622, omitted here to simplify the drawing, being jumpered back to tank 34 by means which will be understood by those skilled in the art.

Valve 620 is provided with operating solenoids 634 and 636. When solenoid 634 is energized, conduit 614 is connected with conduit 628, and conduit 630 is connected with conduit 624. When solenoid 636 is energized, conduit 614 is connected with conduit 630 and conduit 628 is connected with conduit 624. When both solenoids are deenergized, the valve is spring-centered and there is no flow permitted through the valve.

Similarly, valve 622 is provided with solenoids 638 and 640. When solenoid 638 is energized, conduit 618 is connected with conduit 632, and the jumpered outlet from valve 622 is, of course, connected with conduit 626. When solenoid 640 is energized, conduit 632 is connected with conduit 626 and conduit 618 is connected with tank 34 by the jumpered connection referred to above. With both solenoids 638 and 640 deenergized, the valve is centered by its spring and there is no flow permitted.

The positive side 642 of a D. C. power source is shown as being provided with branch conductors 644, 646, 648, 650, 652 and 654. Branch conductor 648 goes to a stationary contact 656; another stationary contact 658 is opposite the contact 656, and a bridging contact 660 is positionable to complete a circuit between the contacts 656 and 658.

Sump and swing cylinders 16 and 18 are provided with the usual piston rods 60 and 62, respectively, and these piston rods themselves carry limit switch actuating projections 74 and 76, respectively. The contacts 656, 658, 660 form a limit switch indicated generally at 664 which corresponds to the limit switch 64 shown in Fig. 4 and the limit switch 364 of Figs. 15 and 16. Similarly, other limit switches 666, 668, 670 and 672 are provided as

shown, as parts of the means to initiate the various operations of the machine.

Limit switch 666 is provided with stationary contacts 674 and 676 and a bridging contact 680. Limit switch 668 is provided with stationary contacts 682 and 684, and a bridging contact 686. Limit switch 670 is provided with stationary contacts 688 and 690, and a bridging contact 692. And limit switch 672 is provided with stationary contacts 694 and 696, and a bridging contact 698.

The limit switches 664, 666, 668 and 670 are connected to operate the selector means comprising valves 620 and 622. They operate the valves 620 and 622 by operating the electromagnetic actuating means consisting of the solenoids 634, 636, 638 and 640. The connection for such operation includes a plurality of electric motor means 700, 702, 704 and 706. Each of the aforesaid electric motor carries a set of normally open contacts and a set of normally closed contacts. Each of the electric motor means also comprises an armature connected to close the normally open contacts and open the normally closed contacts, and a coil connected to be energized by the closing of an appropriate limit switch to move the coil's associated armature.

More specifically, motor means 700 is provided with an armature 708 connected to close normally open contacts 710, 712, 714 and to open normally closed contacts 716, 718, 720. Armature 708 is adapted to be moved by coil 722, one end of which is connected with contact 658 of limit switch 664 by a conductor 724, and the other end of which is connected to the negative side 726 of the D. C. power source by branch conductors 728 and 730.

Electric motor means 702 is provided with an armature 732 carrying normally open contacts 734, 736, 738 and normally closed contacts 740, 742, 744. Armature 732 is adapted to be moved by a coil 746 which has one end connected to contact 674 of limit switch 666 by means of a conductor 748, the other end of the coil being connected with the negative side 726 of the power source by way of conductors 750 and 752.

Electric motor means 704 has an armature 754 which carries normally open contacts 756, 758, 760 and normally closed contacts 762, 764, 766. Armature 754 is adapted to be moved by the energization of a coil 768, one end of which connects with contact 690 of limit switch 670 by a conductor 770, the other end of the coil being connected with the negative side 726 of the line by a branch conductor 772.

Electric motor means 706 has an armature 773 which carries normally open contacts 774, 775, 776 and normally closed contacts 777, 778, 779. Armature 773 is adapted to be moved by a coil 780, one end of which is connected to contact 684 of switch 668 by a conductor 781, and the other end of which is connected to the negative side 726 of the D. C. power source.

The coil of the electromagnetic actuating means 634 of valve 620 is connected with branch conductor 654 by another branch conductor 788 and is connected with the negative side 726 of the power source through conductor 790, normally closed contacts 716, 718, 720 of electric motor means 700, conductor 792, contacts 774, 775, 776 of the normally open set of contacts of electric motor means 706, and branch conductor 794.

The coil of the electromagnetic actuating means 636 is connected with conductor 654 by another branch conductor 796, and with the negative side of the line by a conductor 798, normally open contacts 734, 736, 738 of motor means 702, conductor 800, normally closed contacts 762, 764, 766 of motor means 704, and branch conductor 802.

The coil of the electromagnetic actuating means 638 is connected with branch conductor 654 by another branch conductor 804, and with the negative side of the power source through a conductor 806, normally closed contacts 740, 742, 744 of electric motor means 702,

conductor 808, normally open contacts 710, 712, 714 of electric motor means 700, and branch conductor 728.

The coil of the electromagnetic actuating means 640 is connected with branch conductor 654 by another branch conductor 810, and with the negative side of the power source by means of a conductor 812, normally open contacts 756, 758, 760, conductor 814, normally closed contacts 777, 778, 779 of electric motor means 706 and branch conductor 816.

The automatic means for controlling horizontal swinging of the vein-attacking and disintegrating instrument is for this embodiment substantially the same as in the embodiment shown in Fig. 15, and need therefore not be described again here.

The electrical system of Fig. 18

The system shown in Fig. 18 is a somewhat simplified version of the embodiment shown in Fig. 17. It will be recalled that, in the discussion of Fig. 17, reference was made to the fact that the valves 620 and 622 were shown in the drawing as being connected in parallel with pump 36, but that as an actual matter of fact, the valves might be connected in series. For a series connection, an electrical system something like that shown in Fig. 17 is required for proper operation of valves 620 and 622. However, if these valves can actually be connected in parallel as shown, then a considerably simplified system is possible. Such a system is shown in Fig. 18.

This system eliminates the electric motor means 700, 702, 704 and 706. Instead of connecting the electromagnetic actuating means 634, 636, 638 and 640 through the aforesaid electric motor means, the electromagnetic means are connected for actuation through the limit switches 664, 666, 668 and 670. Inasmuch as the limit switches shown in Fig. 18 are substantially identical with those shown in Fig. 17, they will not be described here in detail.

In the embodiment shown in Fig. 18, the coil 634 is connected across the power source 642, 726 by means of conductor 646, limit switch 668, conductor 818, conductor 820, and conductor 822. Similarly, the coil 636 is connected across the power source 642, 726 by means of conductor 644, limit switch 666, conductor 824, conductor 826, and the aforesaid conductor 822.

In like manner, the coil 638 is connected across the power source by means of conductor 648, limit switch 664, conductor 828, conductor 830, and the aforesaid conductor 822; and the coil 640 is connected across the power source by means of conductor 650, limit switch 670, conductor 832, conductor 834, and the aforesaid conductors 830 and 822.

The electrical means for accomplishing automatic horizontal swinging of the instrument 4 is substantially the same in Fig. 18 as in Fig. 15 and need not be described here in detail.

Operation.—The operation of the embodiment of Fig. 4

It will be assumed that the reader is familiar with the operation of manually operated continuous mining machines made according to the inventions described in the above-identified patent applications to Russell and Sibley. Let us suppose that the vein-attacking and disintegrating instrument has just been lowered from position A into position B (Fig. 20) to begin the summing-in operation, or movement from position B to position C. As the instrument 4 nears the position B, the projection 76 (Fig. 4) engages the limit means (or master cylinder) 68. More specifically, the projection 76 engages the piston rod of the cylinder 68, displacing the piston in its cylinder and effecting a flow of hydraulic fluid through the conduit 80 to the slave cylinder 82. This introduction of hydraulic fluid into cylinder 82 causes movement to the right of the floating piston 86, and with it the skirt 88 which constitutes the control mechanism for the fluid motor 102. As piston 86 moves into the operat-

ing position represented by its extreme limit of travel to the right as seen in Fig. 5, the peripheral groove 90 registers with conduits 96 and 98. The accumulator 106 thereupon discharges hydraulic fluid under pressure through conduit 98, control means 88, conduit 96, and conduit 100 to the fluid motor means 102.

The piston 128 of the hydraulic motor 102 moves to the right, carrying the rack 134 to the right and rotating the pinion 136 clockwise through something more than 90°. As the pinion 136 turns clockwise, the balls 142 in the recesses 140 engage the corners of shaft 138 and rotate it clockwise. The positive rotation of shaft 138 referred to causes the ball detent 156 (Fig. 7) to be forced out of the recess 154 with which it was engaged, 15 and to drop into the next succeeding recess 154. The shaft is then held in the new orientation. Rotation of shaft 138 clockwise as aforesaid effects a rotation of the valve body 170 (Fig. 8) from the position shown in Fig. 11 into the position shown in Fig. 8. Fluid under pressure thereupon flows from the pump discharge line 40 through the axial passage 198 (Fig. 12), into the axial passage 200 of the valve body 170, radially outward through the passage 202 in the valve body 170, through the radial passage 172 in the valve housing 162, through 25 the connecting passage 174, and through conduit 52 to the sump cylinders 16. With valve body 170 in the position shown in Fig. 8, conduit 56 is blanked off and fluid remaining in cylinders 18 is trapped.

As fluid flows into the right end of sump cylinders 16, 30 fluid also flows out of the left end of those cylinders by way of conduit 54, passage 184 in valve body 162, radial passage 182, tangential passage 206 in valve body 170, longitudinal passages 204 and 196, the arcuate passage formed by grooves 188 and 188', the passages formed 35 by groove 186 and its cooperating groove in cover plate 168 and grooves 190, 190', and conduit 50 back to the tank or reservoir 34. As fluid under pressure is admitted to the sump cylinders 16, the vein-attacking and disintegrating bits moving in their orbital paths advance 40 into the vein of coal or other mineral. As the instrument 4 begins to advance in the sump operation, the projection 74 is moved away from the piston rod of the master cylinder 70. The piston of this cylinder is thereupon free to move leftward as seen in Fig. 4. As it 45 moves leftward, spring 104 (Fig. 5) in cylinder 82 forces floating piston 86 to the left as seen in Fig. 5, with the result that the hydraulic fluid that was in cylinder 82 is displaced therefrom through conduit 80 into the master cylinder 70.

With the floating piston 86 of slave cylinder 82 returned once more to the position illustrated in Fig. 5, the peripheral groove 90 is in registry with conduits 92 and 94, with the result that the cylinder of fluid motor 102 is connected with reservoir 34. Spring 130 of fluid motor 102 is thereupon able to push piston 128 leftward again, the hydraulic fluid ahead of piston 128 being discharged into the tank by way of conduits 100, 92, 94 and 50, and the groove 90 of the skirt 88.

As piston 128 moves leftward, it carries with it piston 60 rod 132 and rack 134. Rack 134 thereupon rotates pinion 136 counterclockwise. As pinion 136 rotates counterclockwise, at least one, probably two, and possibly three, of the balls 142 will be carried around the shaft corners into new operating positions, although it may be expected that gravity will cause the ball shown at the right side of Fig. 6 to drop down into the lower end of its recess 140, with the result that the top ball will also usually be out of operating position. Accordingly, at 65 least one of the balls 142 will always be ready to be engaged for another clockwise rotation of pinion 136.

The vein-attacking and disintegrating instrument 4 continues to sum in, and near the end of the summing-in stroke, projection 74 engages the protruding piston rod of the master cylinder 64. Continued movement to the 70 end of the summing-in operation forces the piston in cyl-

15

inder 64 leftward, displacing the hydraulic fluid therefrom into conduit 50 and into slave cylinder 82.

The operation of slave cylinder 82 described above is repeated with the result that the valve body 170 is indexed from the orientation shown in Fig. 8 to the orientation shown in Fig. 9, in which position conduits 52 and 54 are blanked off, and fluid is trapped in cylinders 16.

As is clearly evident from an inspection of Fig. 9 the valve 42 is now oriented into position to admit fluid under pressure from conduit 49 to conduit 56, which connects with the upswing cylinders 18. Inasmuch as the weight of instrument 4 is sufficient to lower that instrument, there is no need to power the instrument down, so that the upswing cylinders 18 are single acting cylinders, and for this stage of operation the tangential passage 206 is blanked off, i. e., is not in communication with any passage in the valve housing 162.

As the instrument 4 begins to swing upward through a vertical plane, the projection 76 moves out of engagement with the piston rod of master cylinder 68, allowing the slave cylinder 82 to return to the position illustrated in Fig. 5, as described above. Furthermore, the fluid motor 102 thereupon returns to the operating position illustrated in Fig. 5 and the valve 42 is in position to be indexed for the next operation.

As the instrument 4 approaches its upper limit of upswing, position D, Fig. 20, projection 76 engages the piston rod of master cylinder 66, effecting once more the operation of slave cylinder 82 referred to above and consequently the operation of fluid motor 102 and the reorientation of valve 42 from the position shown in Fig. 9 to the position shown in Fig. 10. As the valve body 170 rotates clockwise from the position shown in Fig. 9, the radial passage 202 moves out of registry with the radial passage 176 with the result that the radial passage 176 is blanked off, as shown in Fig. 10. Fluid is thereupon trapped in the upswing cylinders and the instrument 4 is held in its uppermost operating position.

With the valve body 170 in the position shown in Fig. 10, fluid under pressure is admitted from the pump discharge line 40 to the left end of the sump cylinders 16 by way of the conduit 54. At the same time the right ends of sump cylinders 16 are connected with the tank 34 by way of conduits 50 and 52, and the appropriate passages in valve 42.

With the connections shown in Fig. 10 and described above, hydraulic fluid under pressure is forced into the left ends of cylinders 16 and is discharged from the right ends, with the result that the vein-attacking and disintegrating instrument 4 moves through the operation called "retract."

As the instrument 4 begins to retract, the projection 74 moves out of engagement with the piston rod of master cylinder 64, allowing the slave cylinder 82 to return to neutral and permitting the fluid motor 102 to return to its neutral position, all as has been described above in detail. Fluid motor 102 is thereupon again in position to index the selector means 42 for the next operation.

As the instrument 4 nears the end of the retracting operation, the projection 74 engages the piston rod of master cylinder 70, effecting operation of slave cylinder 82. With the piston 86 of the slave cylinder 82 moved to the extreme right, as seen in Fig. 5, hydraulic fluid under pressure is again admitted to fluid motor 102, and the valve 42 is indexed into its next operating position, namely, from the position shown in Fig. 10 to the position shown in Fig. 11, again trapping fluid in cylinders 16.

In the position shown in Fig. 11, valve body 170 is so oriented that the tangential passage 206 is in communication with the radial passage 176, so that the upswing cylinders 18 are connected with the tank 34 by way of conduit 56, valve 42, and conduit 50. The weight of the instrument 4 is sufficient to force the discharge of hydraulic fluid from the cylinders 18. Those cylinders are therefore single acting cylinders, and the radial pas-

16

sage 202 of valve body 170 is blanked off in the orientation of valve 42 as shown in Fig. 11.

As the instrument 4 begins to lower, the projection 76 moves out of engagement with the piston rod of master cylinder 66, allowing slave cylinder 82 to return to its neutral operating position as shown in Fig. 5, whereupon fluid motor 102 also returns to neutral and into position for the next indexing step. As the instrument 4 reaches its lowermost position, projection 76 engages the piston rod of master cylinder 68, operating the slave cylinder 82 and causing fluid motor 102 to index the valve 42 from the position shown in Fig. 11 to the position shown in Fig. 8. The instrument 4 is thereupon ready to begin a new cycle of operation.

It will, of course, be understood by those skilled in the art that, without the intervention of another operation, the instrument 4 would be in position to move through an operation in a space which had already been cleared of coal or other mineral by the cycle of operations just described. Some means is required to index the instrument 4 horizontally about its vertical axis of swing into a new operating position. The horizontal swinging of the instrument 4 is accomplished by the swing cylinders 20.

Reference is made again to that portion of the cycle in which the sump cylinders 16 retract the instrument 4 from its extended position. As the instrument 4 nears its completely retracted position, the projection 78 on piston rod 60 (Fig. 4) engages the protruding piston rod of master cylinder 72. Master cylinder 72 is constructed and operates in a manner substantially the same as master cylinders 64, 66, 68 and 70. As master cylinder 72 is operated, it effects operation of slave cylinder 212, which is substantially the same as slave cylinder 82. As slave cylinder 212 is moved into position in response to the actuation of master cylinder 72, communication between conduits 230 and 232 is cut off, and communication between conduits 224 and 226 is established. Fluid under pressure is thereupon free to move from accumulator 106 through conduits 110, 98 and 224, the control groove of slave cylinder 212, conduits 226, 228, 250 and 252.

It should be noted that fluid under pressure is also admitted at this time to the valve 234. It will be assumed for the moment that valve 234 is so oriented as to connect conduit 228 with conduit 240 and conduit 236 with conduit 238. Conduit 240 is therefore under pressure but because the conduit is still blanked off with piston 268 in the position shown in Fig. 4, there is of course no fluid flow through conduit 240.

Piston 268 is free to move leftward as seen in Fig. 4 under the influence of fluid pressure introduced by way of conduit 252. Accordingly, piston 268 moves to the left, compressing spring 270, until conduit 246 is connected with conduit 238 by way of groove 272, and conduit 248 is connected with conduit 240 by way of groove 274. Fluid thereupon flows from conduit 240 through groove 274 and conduit 248 into the right ends of the swing cylinders as seen in Fig. 4; at the same time fluid is discharged from the left ends of the swing cylinders by way of conduit 246, groove 272, conduit 238, valve 234, and conduits 236, 94, and 50 to the tank 34.

The swing cylinders 20 effect horizontal swinging (see Fig. 19) of the instrument 4 about its vertical axis at the same time that the instrument 4 is being lowered. This horizontal swinging brings about a relative movement between cam follower 278 and the cams 282, 284 and 286. It will be assumed that the relative movement is such that cam 286 and cam follower 278 are moving toward each other.

As the cam 286 engages the cam surface 280 of cam follower 278, cam follower 278 is pivoted clockwise as seen in Fig. 4 until the extension 298 engages the stop 296. Continued swinging of the instrument 4 causes the cam 286 to push the cam follower 278, and therefore piston 268, to the right as seen in Fig. 4.

As soon as piston 268 is moved to the right sufficiently

to move the grooves 274 and 272 out of engagement with conduits 240, 248, and 238, 246, respectively, the horizontal swinging of instrument 4 stops. Cam follower 278 remains in contact with cam 286 until the pressure in cylinder 244 is relieved. It will be noted that, as soon as the sump cylinders 16 begin their sumping-in operation, projection 78 will move out of engagement with the limit means, or master cylinder, 72, allowing the slave cylinder 212 to return to its neutral position, in which communication is cut off between conduits 224 and 226 and is established between conduits 230 and 232, whereupon cylinder 244 is vented by way of conduits 252, 250, 228 and 230, the control groove of slave cylinder 212, and conduits 232, 94 and 50 to the tank 34. Conduit 254 and check valve 256 connect with pump line 40 in order to provide a safety pressure outlet in case piston 268 be moved to the right at a time when, for any reason, conduit 250 might be blocked.

Spring 270 is now free to push piston 268 further to the right as seen in Fig. 4, permitting cam follower 278 to be snapped into its central operating position as shown in Fig. 4 by its centering spring, not shown. Cam follower 278 is then positioned so as to be able to clear the cam with which it was just in engagement the next time piston 268 moves leftward.

It can thus be seen that as each of the cams 282, 284, 286 etc. engages cam follower 278 the lateral movement of the disintegrating instrument is interrupted after the latter has moved through a normal operating stroke distance, i. e. considering that the full relative movement of the cylinders 20 and their associated pistons causes lateral movement of the disintegrating instrument through a distance which is a multiple of the normal operating stroke distance required to move the disintegrating instrument into position to start another cycle, the disintegrating instrument moves through a normal stroke distance into a new cycle starting position as each of the successive cams 282, 284, 286 etc. comes in contact with the cam follower 278 and causes an interruption of fluid flow to cylinders 20.

As will be understood by those skilled in the art, the mechanism may be oriented for swinging in the opposite direction by reversing the four-way valve 234 to bring conduits 228 and 238 in communication, and conduits 236 and 240 in communication; and by swinging the cam follower 278 through 180° about the axis of piston rod 276.

It will further be understood by those skilled in the art that horizontal swinging of the instrument 4 may be accomplished manually independently of the automatic mechanism by manipulation of valve 258.

The operation of the embodiment of Fig. 15

The embodiment shown in Fig. 15 employs a selector valve 42 which is identical with the selector valve shown in Fig. 4, but is electrically operated. As instrument 4 reaches its lowermost position in the "lower" operation of its cycle, projection 76 engages the limit switch 368, closing the normally open contacts 406, 410, 408 and 446, 448, 386.

It will be recalled that the instrument 4 is in the "retract" position as it swings down through the "lower" operation of the cycle. With the instrument 4 retracted, the limit switch 370 is in its closed position, i. e., the position shown in Fig. 15. The closing of limit switch 368 referred to above completes an electric circuit from the positive side 317 to the negative side 329 of the power source through conductors 318 and 374, coil 332, conductor 376, conductor 390, closed contacts 388, 416, 414 of limit switch 370, conductor 412, closed contacts 408, 410, 406 of limit switch 368, and conductor 404. With coil 332 thus energized, armature 334 is moved to close contacts 322, 330, and 324. A circuit is thereupon established from positive side 317, through conductor 318, coil 312 of electromagnetic device 310, con-

ductor 320, closed contacts 322, 330, 324, and conductors 326 and 328 to the negative side 329.

With coil 312 thus energized, armature 314 is moved to the right to index the selector valve 42 into the position, shown in Fig. 8. Fluid under pressure is thereupon admitted to effect sumping of the instrument 4. As the sumping-in operation begins, projection 74 moves out of contact with limit switch 370, allowing the contacts thereof to open. This opening of the contacts breaks the circuit outlined above for coil 332 and allows the contacts 322, 330, and 324 to open, which in turn breaks the circuit for coil 312. With coil 312 thus de-energized, spring 316 is free to retract the rack 134' into the position shown in Fig. 15, whereupon the electromagnetic device is ready to orient the selector valve 42 for the next operation.

As the instrument 4 nears the end of its sumping-in operation, projection 74 on piston rod 60 closes the contacts of limit switch 364. An electric circuit is then established from positive side 317, through conductors 318 and 374, coil 332, conductors 376 and 380, contacts 386, 448, 446 of limit switch 368, conductor 444, contacts 440, 442, 436 of limit switch 364, and conductor 438 to the negative side 329.

Bridging contact 330 thereupon moves again into circuit closing position, and a circuit is established again for the coil 312 as described above. With coil 312 thus energized again, valve 42 is indexed from the position shown in Fig. 8 into the position shown in Fig. 9, so that fluid under pressure is admitted to the upswing cylinders 18.

As the instrument 4 begins to move through the upswing operation, projection 76 moves out of contact with limit switch 368, allowing the contacts of limit switch 368 to open and thus opening the circuit for coil 332 just detailed above. Coil 332 is again de-energized, again breaking the circuit for coil 312 and again returning the electromagnetic device 310 into position for orientation of the valve 42 for the next operation.

As the instrument 4 nears the uppermost limit of upswing, projection 76 engages the limit switch 366 and closes its contacts. A circuit is thereupon established from the positive side 317 through conductors 318 and 374, coil 332, conductors 376 and 378, contacts 382, 394, 392 of limit switch 364, conductor 396, contacts 398, 402, 400 of limit switch 366, and conductor 404 to the negative side 329.

Bridging contact 330 is thereupon again moved into circuit closing position for coil 312, indexing the valve 42 from its orientation shown in Fig. 9 to the orientation shown in Fig. 10. Fluid is thereupon admitted to the sump cylinders 16 to move them through the "retract" operation of the cycle. As the sump cylinders begin to retract, projection 74 moves out of contact with limit switch 364, allowing the contacts thereof to open and thus opening the circuit for coil 332 just detailed. This de-energization of coil 332 again allows the contact 330 to drop out, thus opening the circuit for coil 312. Electromagnetic device 310 is thereupon returned again into position for once more indexing the valve 42 for the next operation.

As the instrument 4 approaches the end of the "retract" operation, projection 74 engages limit switch 370 and closes the contacts thereof. A circuit is thereupon established from positive side 317 through conductors 318 and 374, coil 332, conductors 376 and 378, contacts 384, 420, 418 of limit switch 366, conductor 422, contacts 424, 428, 426 of limit switch 370, and branch conductor 430 to the negative side 329.

Coil 332 is thus again energized to complete an electric circuit for coil 312 and to move selector valve 42 from the position shown in Fig. 10 to the position shown in Fig. 11. With the valve in the position shown in Fig. 11, the upswing cylinders 18 are vented to the tank 34, and the weight of instrument 4 causes it to lower as fluid is discharged from cylinders 18 to tank 34. As instru-

ment 4 begins to lower, projection 76 is disengaged from the limit switch 366 allowing the contacts thereof to open and thus breaking the circuit just detailed for coil 332.

The resultant de-energization of coil 332 again interrupts the circuit for coil 312, whereupon electromagnetic device 310 is again returned to its position for again indexing valve 42. The machine is then once more in position to start a new cycle.

It will be noted that the machine will proceed to move through a cycle of operation in a space which has just been evacuated of coal or other mineral, unless the vein-attacking and disintegrating instrument is indexed through a given arc about its vertical axis. This is accomplished by limit switch 372 and the mechanism shown in the lower portion of Fig. 15. The arm or projection 78 engages the limit switch 372, closing the contacts thereof. As the contacts of limit switch 372 close, a circuit is completed from the positive side 317 of the D. C. power source by way of conductor 504, limit switch 372, conductor 498, conductor 516, coil 528, conductor 532, conductor 482, and conductor 328 to the negative side 329 of the line.

When coil 528 is energized, it of course attempts to open the contacts 520, 524, 526. Note, however, that the solenoid of which coil 528 forms a part is a time-delay opening solenoid. Accordingly, the contacts do not open immediately upon the energization of coil 528. These contacts complete an electric circuit as follows: positive side 317, limit switch 372, conductor 598, conductor 516, conductor 518, contacts 520, 524, 522, conductor 526, conductor 490, coil 484, conductor 488, conductor 482, and conductor 328 to the negative side 329 of the D. C. power source.

The energization of coil 484 closes the normally open contacts 478, 480, 476. The closing of these contacts completes a circuit through the switch or valve 450 as follows: positive side 317 of the D. C. power source, conductor 318, conductor 472, valve 450, conductor 474, closed contacts 476, 480, 478, and conductors 482 and 328 back to the negative side 329 of the line.

With the solenoid of valve 450 energized, valve 450 opens, permitting fluid under pressure to flow from conduit 40, through conduit 264, valve 450 to conduit 454, through valve 456 to either conduit 458 or 460 depending upon the orientation of valve 456. At the same time, fluid flows from the other one of conduit 458 or 460 back through valve 456, conduit 452, valve 450, and conduit 266 to the reservoir 34.

With the fluid flow as just established, the vein-attacking and disintegrating instrument begins to swing about its vertical axis. As the instrument swings through a small degree, the cam follower 512 moves off the cam 508, allowing the contacts 492, 496, 494 to close and complete a circuit which by-passes or parallels the normally closed contacts 520, 524, 522. The circuit through the contacts 492, 496, 494 will be established before the contacts 522, 524, 520 are opened by the time-delay opening relay.

With the contacts 492, 496, 494 closed, there is a circuit which we may call a holding circuit through the coil 484 as follows: positive slide 317 of the line, conductor 504, limit switch 372, conductor 498, contacts 494, 496, 492, conductor 490, coil 484, conductors 488, 482, and 328, back to the negative side 329 of the power source. This circuit constitutes a holding circuit for coil 484, which circuit remains closed until instrument 4 has indexed through the desired arc.

As long as the circuit just detailed is complete, fluid continues to flow to the swing cylinders through the valve 450 and the valve 456. The vein-attacking and disintegrating instrument continues to swing until the cam follower 512 comes into contact with another cam such as the cam 507, 508 or 510. Let it be assumed that the instrument is swinging in such a direction that cam follower

512 and cam 510 have relative movement toward each other. As soon as cam follower 512 is pushed to the right by cam 510, contacts 494, 496, 492 open. Inasmuch as contacts 520, 524, 522 are already open by this time, the opening of contacts 494, 496, 492 opens the circuit of coil 484. With coil 484 thus deenergized, contacts 476, 480, 478 open, de-energizing the operating coil of valve 450. Valve 450 thereupon closes and the instrument 4 stops swinging about its vertical axis. Instrument 4 is then oriented to begin a new operating cycle.

The operation of the embodiment of Fig. 16

Reference is now made to Fig. 16 for a description of the operation of the embodiment shown therein. The selector valve 542 shown in Fig. 16 is substantially the same as the selector valve for the embodiment shown in Fig. 4 with the exception that the selector valve 542 is not moved by a rack and pinion mechanism but is moved by direct connection with an electric motor, the armature of which is shown at 534.

The description of operation will begin with the vein-attacking and disintegrating instrument in the fully retracted position, in which position the limit switch 370 is closed, and with the vein-attacking and disintegrating instrument moving downward through the "lower" portion of the cycle. As the instrument 4 approaches the lowermost position, the arm or projection 76 engages the limit switch 368 and closes the contacts thereof.

An electric circuit is thereupon established as follows: from the positive side 546 of the D. C. power source, conductor 578, limit switches 370 and 368, conductors 404, 576, and 574, time-delay-opening contacts 572, 570, 568, conductor 566, coil 562, and conductor 558, back to the negative side 560 of the power source. The circuit detailed energizes the coil 562 and effects a closing of the normally open contacts 552, 556, 554.

An electric circuit is thereupon established as follows: from the positive side 546 of the line, through conductor 548, armature 534, conductor 550, contacts 552, 556, 554, and conductor 558 to the negative side 560 of the D. C. power source. The circuit thus establishes a power circuit for the valve drive motor, of which the armature 534 forms a part, and the motor begins to rotate, turning with it the rotatable valve body of the valve 542.

As the motor shaft 598 rotates, it turns the cams 610 and 594. As cam 594 rotates, the lobe 596 moves out from under cam follower 592 and contacts 588, 586 of switch 584 are allowed to close. It will be noted that there has meanwhile also been established an electric circuit through the coil 580, as follows: from the positive side of the power source 546, through conductor 578, limit switches 370 and 368, conductors 404, 576, and 574, coil 580, and conductor 558 to the negative side 560 of the power source. The coil 580 opens the contacts 568, 570, 572 after a predetermined time has elapsed. That time is longer than the time it takes for the contacts 588, 586 of switch 584 to close, so that there is a holding circuit through the switch 584 before the TDO contacts 568, 570, 572 open. The circuit through the contacts 568, 570, 572.

Meanwhile cam 610 has also rotated, with the result that cam lobe 612 has moved out from under cam follower 608, permitting the contacts 602, 604 of switch 600 to close. Limit switch 600 is connected in parallel with the limit switches 364, 366, 368, 378 so that when limit switch 600 is closed, it no longer matters to the circuit of coil 580 and to the circuit of the motor armature 534 what happens to the limit switches 364-370. The motor circuit is thereupon allowed to continue because the holding circuit for coil 562 is as follows: from positive side 546 of the D. C. power source, through a portion of conductor 578, cam follower 608, limit switch 600, conductors 606 and 574, cam follower 592, limit switch 584, conductor 590, coil 562, and conductor 558 back to the negative side 560 of the power source.

The holding circuit thus established continues until the cam lobe 612 again raises the cam follower 608, opening the limit switch 600 and interrupting the circuits for coils 562 and 580. With coil 562 de-energized, the contact 556 drops out of engagement with contacts 552 and 554 and interrupts the armature circuit for the motor which turns valve 542. With coil 580 de-energized, TDO contacts 572, 570, 568 close again and are once more in position to complete a circuit for coil 562 the next time one of limit switches 364, 366, 368, 370 is closed.

With valve 542 thus indexed into its next operating position, fluid under pressure is admitted to the right end of the sump cylinders 16 as seen in Fig. 16, and the vein-attacking and disintegrating instrument begins to move into the coal or other mineral.

As the instrument 4 approaches the end of the sump stroke, the projection 74 engages the limit switch 364 and closes the contacts thereof. The circuit for coil 562 is thereupon established as follows: from positive side 546 of the power source, through conductor 578, limit switch 368, limit switch 364, conductors 438, 576, and 574, TDO contacts 572, 570, 568, conductor 566, coil 562, and conductor 558 back to the negative side 560 of the power source.

The armature 534 and the limit switches 584 and 600 thereupon move through the same cycle of operation detailed above, effecting an indexing of the valve 542 to the next operating position, in which fluid under pressure is admitted to the upswing cylinders 18.

As the vein-attacking and disintegrating instrument nears the upper-most limit of its upswing, projection 76 engages the limit switch 366 and closes the contacts thereof. An electric circuit for coil 562 is thereupon established as follows: positive side 546, conductors 578 and 378, limit switch 364, conductor 396, limit switch 366, conductors 404, 576, and 574, TDO contacts 572, 570, 568, conductor 566, coil 562, and conductor 558 back to the negative side 560 of the power source. With coil 562 thus energized, a circuit is again established for the armature of the electric motor and valve 542 is indexed into its next operating position.

With valve 542 indexed into its next operating position, the pump delivers fluid under pressure to the left ends of sump cylinders 16, effecting the retraction of the vein-attacking and disintegrating instrument 4. As instrument 4 nears its rearmost position, the projection 74 engages limit switch 370 and establishes an electric circuit as follows: from positive side 546 through conductors 578 and 378, limit switch 366, conductor 422, limit switch 370, conductors 430, 576 and 574, and TDO contacts 572, 570, 568, conductor 566, coil 562, and conductor 558 back to the negative side 560. With coil 562 energized by the circuit thus detailed, the bridging contact 556 again moves into circuit closing position and establishes a circuit for armature 534. Valve 542 is thereupon indexed into its next position in which fluid is allowed to discharge from the upswing cylinders 18 permitting the vein-attacking and disintegrating instrument 4 to move downward through the "lower" step in the cycle of operations. Instrument 4 is now in position to begin another cycle of sump, upswing, retract, and lower.

The mechanism for indexing instrument 4 horizontally (i. e., about its vertical axis) is the same as in the embodiment of Fig. 15, and will not be described again here.

The operation of the embodiment of Fig. 17

Reference is now made to Fig. 17 for a description of the operation of the embodiment of the invention shown in that figure. With the vein-attacking and disintegrating instrument in its fully retracted position and moving downward in the "lower" portion of the cycle,

the arm or projection 74 is already in engagement with limit switch 670 and the contacts 688, 692, 690 are closed. As the instrument 4 reaches the end of its "lower" position, arm 76 engages limit switch 668 and closes the contacts 684, 686, 682. An electric circuit is thereupon established from the positive side 642 of the D. C. power source through conductor 646, contacts 682, 686, 684 of limit switch 668, conductor 781, coil 780 of electric motor means 706, to the negative side 726 of the power source. At this point in the cycle of operations, electric motor means 704 (or, more accurately, coil 768 thereof) remains energized, and the coils of electric motor means 700 and 702 remain de-energized, with the result that the operating coils 636, 638, and 640 of valves 620 and 622 are de-energized. Coil 634 is energized, as will now be explained.

With coil 780 energized, the normally closed contacts 779, 778, 777 are opened and the normally open contacts 774, 775, 776 are closed. An electric circuit is thereupon established from the positive side 642 of the power source through conductor 654, conductor 788, coil 634, conductor 790, contacts 716, 718, 720, conductor 792, contacts 774, 775, 776, and conductor 794 back to the negative side 726.

With the solenoid 634 thus energized, fluid under pressure flows from the pump 36, through conduits 40 and 614, valve 620, and conduit 628 to the sump cylinders 16 to effect sumping-in of the vein-attacking and disintegrating instrument 4.

As the instrument 4 begins to move into the vein of coal or other mineral, projection 74 moves away from or out of contact with the limit switch 670, allowing contacts 688, 692, 690 of limit switch 670 to open. With limit switch 670 thus de-energized, coil 768 of electric motor means 704 is de-energized, and normally closed contacts 762, 764, 766 are again allowed to close, while the contacts 756, 758, 760 open.

As the instrument 4 nears the end of its sumping-in stroke, projection 78 engages and closes limit switch 664, establishing a circuit as follows: positive side 642 of the power source, conductor 648, contacts 656, 660, 658 of limit switch 664, conductor 724, coil 722 of electric motor means 700, and conductors 730 and 728 to the negative side 726 of the power source.

The circuit just detailed energizes the coil 722 of electric motor means 700, opening the normally closed contacts 716, 718, 720 and interrupting the circuit for the coil 634 detailed above. Valve 620 returns to its center or closed position, and fluid is trapped in the sump cylinders 16. At the same time, the normally open contacts 710, 712, 714 are closed and a circuit is established as follows: from the positive side 642 of the power source through conductors 654 and 804, coil 638, conductor 806, normally-closed contacts 740, 742, 744 of electric motor means 702, conductor 808, contacts 710, 712, 714 and conductor 728 to the negative side 726 of the power source.

With the coil of solenoid 638 thus energized, fluid under pressure is permitted to flow from pump 36 through conduits 40 and 618, valve 622, and conduit 632 to the upswing cylinders 18. As the vein-attacking and disintegrating instrument 4 begins to move upward, projection 76 is disengaged from the limit switch 668, allowing contacts 684, 686, 682 to open and interrupting the circuit

for coil 780 of electric motor means 706, permitting the normally closed contacts 777, 778, 779 to close and permitting the normally open contacts 774, 775, 776 to open. With the latter set of contacts thus opened, the circuit for the coil of solenoid 634 continues broken and self-centering valve 620 remains in its central or valve closed position.

As the upswing cylinders move the instrument 4 upward toward the upper limit of travel, projection 76 engages limit switch 666 and establishes an electric circuit as

follows: from positive side 642 through conductor 644, contacts 676, 680, 674 of limit switch 666, conductor 748, coil 746 of electric motor means 702, conductor 752, and conductors 750 and 752 back to the negative side 726 of the power source.

With coil 746 of electric motor means 702 thus energized, the normally closed contacts 740, 742, 744 are opened, de-energizing the coil 638 and allowing valve 622 to return to its central or valve closed position and thus trapping fluid in the upswing cylinders. Meanwhile, the normally open contacts 734, 736, 738 are closed completing an electric circuit as follows: from positive side 642 of the power source, through conductors 654 and 796, coil 636, conductor 798, now-closed contacts 734, 736, 738, conductor 800, normally closed contacts 762, 764, 766, and conductor 802 to the negative side 726.

With the coil of solenoid 636 thus energized, valve 620 is moved into position to connect conduit 614 with conduit 630 and to connect conduit 628 with conduit 624. This connection allows fluid under pressure to flow to the left end as seen in Fig. 17 of the sump cylinders 16, moving those sump cylinders and instrument 4 through the "retract" operation of the cycle.

As the sump cylinders begin to retract, projection 78 moves out of engagement with limit switch 664, permitting contacts 656, 666, 658 to open and de-energizing the coil 722 of electric motor means 700. This allows the normally open contacts 710, 712, 714 to open, thus assuring a continued open circuit for coil 638.

As the sump cylinders approach the end of the "retract" position, projection 74 engages limit switch 670 and closes the contacts thereof to complete an electric circuit as follows: from positive side 642, through conductor 650, contacts 688, 692, 690 of limit switch 670, conductor 770, coil 768 of electric motor means 704, and conductor 772 back to the negative side 726 of the power source.

With coil 768 thus energized, the normally-closed contacts 762, 764, 766 open to break the energizing circuit for the coil of solenoid 636, thus permitting self-centering valve 620 to return to its central or no-flow position and trapping fluid in the sump cylinders 16.

The energization of coil 768 closes the normally-open contacts 756, 758, 760 to complete an electric circuit as follows: from the positive side 642, through conductors 654, and 810, coil 640, conductor 812, now-closed contacts 756, 758, 760 of electric motor means 704, conductor 814, normally-closed contacts 777, 778, 779 of electric motor means 706, and conductor 816 back to the negative side 726 of the line.

With the coil of solenoid 640 thus energized, the conduit 632 is put in communication with conduit 626 through valve 622, and the vein-attacking and disintegrating instrument is permitted to lower because fluid discharges from the upswing cylinders. The machine is thereupon ready to repeat the cycle which is described above.

Inasmuch as the mechanism to effect horizontal swinging of the vein-attacking and disintegrating instrument about its vertical axis is substantially the same in the embodiment shown in Fig. 17 as in Fig. 15, it need not be repeated here.

The operation of the embodiment of Fig. 18

Reference is now made to Fig. 18 for a better understanding of the operation thereof.

As the vein-attacking and disintegrating instrument moves through the "lower" portion of the cycle, the instrument 4 is of course in its fully retracted position, with the result that the limit switch 670 is already closed. As the instrument 4 nears the end of the "lower" portion of the cycle, the limit switch 668 is closed by projection 76 and an electric circuit is established as follows: from the positive side 642, through conductor 646, limit switch 668, conductor 818, coil 634, conductors 820 and 822, to the negative 726 of the D. C. power source.

With coil 634 thus energized, the pump 36 pumps fluid

under pressure to the sump cylinders 16 and the instrument 4 moves into the vein of coal or other mineral. As the instrument 4 moves forward, projection 74 moves away from the limit switch 670 and allows it to open, thus interrupting the circuit for coil 640, permitting valve 622 to return to its centered or closed position and trapping fluid in the cylinders 18.

As the instrument 4 nears the end of its summing-in operation, limit switch 664 is closed and establishes an electric circuit as follows: from positive side 642, through conductor 648, limit switch 664, conductor 828, coil 638, conductors 830 and 822, back to the negative side 726 of the power source.

With the coil of solenoid 638 thus energized, valve 622 is moved into position to connect the pump 36 with the upswing cylinders 18 and the instrument 4 begins to move in the upswing portion of the cycle. As the instrument begins to move upward, projection 76 moves out of engagement with the limit 668, which opens to interrupt the previously established circuit for the coil 634 and allows valve 620 to return to its centered or closed position, trapping fluid in cylinders 16. As the instrument nears its upper limit of travel during upswing, the limit switch 666 is closed and an electric circuit is established as follows: from the positive side 642 through conductor 644, limit switch 666, conductor 824, coil 636, and conductors 826 and 822 back to the negative side 726 of the power source.

With the coil of solenoid 636 thus energized, the valve 620 is oriented so as to admit fluid under pressure to the left end of sump cylinders 16, thus initiating the "retract" portion of the cycle.

As the sump cylinders begin to retract, limit switch 664 opens, thus interrupting the circuit previously established for coil 638, permitting valve 622 to return to its centered position and trapping fluid in cylinders 18.

As the sump cylinders 16 approach the end of the "retract" operation, limit switch 670 is closed and establishes an electric circuit as follows: from the positive side 642, through conductor 650, limit switch 670, conductor 832, coil 640, conductors 834, 830 and 822, back to the negative side 726 of the power source.

With the coil of solenoid 640 thus energized, the valve 622 is moved into position to connect conduit 632 from the upswing cylinders with the discharge conduit 626 and the tank 34, allowing the upswing cylinders to discharge fluid to the tank and permitting the vein-attacking and disintegrating instrument to move through the "lower" operation of the cycle whereupon the instrument is again in position to begin the cycle of operations described above.

Inasmuch as the mechanism for effecting horizontal swinging of the vein-attacking and disintegrating instrument is substantially the same in the embodiment shown in Fig. 18 as in the embodiment shown in Fig. 15, it will not be considered necessary to repeat the description of operation of the horizontal swinging here.

It will be appreciated by those skilled in the art that this invention sets forth a much improved method for automatic operation of a continuous mining machine and requiring less labor for the operation. Other advantages will be readily apparent to those skilled in the art.

While there are in this application specifically described five forms which the invention may assume in practice, it will be understood that these forms of the same are shown for purpose of illustration, and that the invention may be modified and embodied in various other forms without departing from the spirit or the scope of the invention as set forth in the appended claims.

70 I claim:

1. In a continuous mining machine, a vein-attacking and disintegrating instrument, means to move said instrument through a cycle of a plurality of operations, and an automatic control system comprising means responsive to completion of an operation for initiating the next opera-

tion of the cycle including: a plurality of limit means, one for each operation and arranged to be actuated upon completion of its associated operation; selector means having a given orientation for each operation of said instrument; motor means connected to orient the selector means for the several operations of the instrument and means connected to be operated by actuation of said limit means for controlling the energization of said motor means.

2. A mining machine as in claim 1, in which the motor means is a rotary electric motor connected to orient the selector means, said automatic control system including means to stop the electric motor after rotation through a predetermined arc.

3. A mining machine as in claim 2, in which the last-named means includes a normally open contactor, electromagnetic means to close the contactor; and a control circuit for said electromagnetic means, said control circuit including a set of normally closed contacts and a limit switch connected in parallel.

4. A mining machine as in claim 3, and a second limit switch in parallel with said limit means and in series with the first-named limit switch.

5. A mining machine as in claim 4, in which the first- and second-named limit switches are operated by the electric motor.

6. In a continuous mining machine, a vein-attacking and disintegrating instrument, means to move said instrument through a cycle of a plurality of operations, and an automatic control system comprising means responsive to completion of an operation for initiating the next operation of the cycle including: a system having a plurality of limit means, one for each operation and arranged to be actuated upon completion of its associated operation; motor means connected to be operated by actuation of said limit means; selector means having a given orientation for each operation of said instrument; means to change the orientation of the selector means; and control means for said orientation changing means, the control means being connected for operation by said motor means.

7. A mining machine as in claim 6, in which said orientation-changing means includes a fluid motor and a source of supply of fluid under pressure connectible to supply fluid to the fluid motor, the aforesaid control means being connected alternatively to admit fluid under pressure to the fluid motor and to vent fluid from that motor.

8. A machine as in claim 6, in which the limit means comprise hydraulic pumps in a common circuit having a normally fixed volume; and the motor means is a hydraulic motor connected in the common circuit; whereby operation of one of the hydraulic pumps serves to operate the hydraulic motor.

9. A machine as in claim 8, in which the orientation-changing means includes a fluid motor and means connecting said fluid motor with a source of fluid under pressure and with an exhaust constituting a hydraulic circuit which is independent of said common circuit, said control means operative to selectively connect said fluid motor with said fluid pressure source and with said exhaust.

10. In a continuous mining machine, a vein-attacking and disintegrating instrument, a plurality of hydraulic motors connected to move said instrument through a cycle of a plurality of operations, a source of hydraulic fluid under pressure connected to operate said motors, and an automatic control system comprising means responsive to completion of an operation for connecting said source to operate the appropriate hydraulic motor for the next succeeding operation and including: a plurality of limit means, one for each operation and arranged to be actuated upon completion of its associated operation; selector means connected to control the flow of hydraulic fluid to said motors and having a given orientation for each operation of said instrument; means to

change the orientation of the selector means; control means for the orientation changing means; and motor means operable upon operation of said limit means and connected to operate the control means.

5 11. A mining machine as set forth in claim 10, in which the orientation-changing means includes a rack and pinion, and a motor connected to drive the rack.

12. A mining machine as in claim 11, in which the motor means is a fluid motor comprising a cylinder and piston mechanism, and the control means includes a grooved skirt on the piston of said mechanism.

13. A mining machine as in claim 12, in which the limit means include a plurality of fluid pumps having a common connection with the cylinder of said fluid motor and actuatable in a predetermined sequence one at a time.

14. A machine as in claim 10, in which the orientation-changing means includes a fluid motor; and means, including the control means, to supply fluid under pressure to the motor of the orientation-changing means.

20 15. A machine as in claim 10, in which the means responsive to completion of an operation also includes electric circuits, the limit means comprising limit switches, and the selector means being connected to be controlled by said circuits.

16. A machine as in claim 15, and electric motor means connected to be operated upon the closing of a limit switch.

30 17. A machine as in claim 10, the control means comprising a set of normally open contacts; and electric motor means connected to close the contacts upon actuation of one of the limit means.

35 18. A machine as in claim 17, in which the orientation-changing means comprises a rotary electric motor; the control means including means to stop the rotary electric motor after rotation through a predetermined arc.

19. A machine as in claim 17, the orientation-changing means including reciprocal mechanism and an electromagnetic device.

40 20. In a continuous mining machine, a vein-attacking and disintegrating instrument, and supporting and moving means for said instrument including means for moving said instrument successively through like cycles of vein-attacking operations in an upright plane, and means for repositioning said instrument between successive cycles of vein-attacking operations to provide for their successive performance on laterally contiguous portions of an upright face, and controlling means for said supporting and moving means and said repositioning means, including a hydraulic circuit having a slave cylinder and a plurality of master cylinders, the master cylinders constituting limit means actuated upon the completion of each operation of said vein-attacking cycle, selector means having a given orientation for each operation, and means connected to and controlled by the slave cylinder to change the orientation of the selector means.

21. A mining machine as in claim 20, in which the orientation-changing means includes a second hydraulic circuit having a source of fluid under pressure, a control valve, and an operating cylinder, the control valve being operated by the aforesaid slave cylinder.

60 22. In a continuous mining machine having a vein-attacking and disintegrating instrument, means to move said disintegrating instrument through a cycle of operations including means to move said instrument into and to withdraw the instrument from a vein of solid mineral, means to move the instrument in one direction substantially transverse to the direction of movement into and out of the vein, and means to move the instrument in another direction substantially transverse to the direction of movement into and out of the vein and through a stroke distance which is a multiple of the normal operating stroke distance for each cycle of operation, an

70 75

automatic control system comprising: means to initiate action of the second-named means upon movement of the instrument into the vein a predetermined distance, means to initiate withdrawal action of the first-named means upon movement of the instrument a predetermined distance in said one direction, means to initiate action to move the instrument into position for starting another cycle upon completion of withdrawal, means to initiate action to move the instrument in said other direction upon completion of withdrawal and to arrest such movement after it has progressed through the normal operating stroke distance, said means including cam operated mechanism, and means to initiate action of the first-named means to move the instrument into the vein upon arrival of the instrument in said position for starting another cycle.

23. A mining machine as in claim 22, in which the means to move the instrument in said other direction comprises a hydraulic system, the aforesaid cam operated mechanism including a plurality of cams and a cam follower and said action initiating means also including a valve in said hydraulic system having one operating position to permit fluid flow to effect movement in said other direction and being movable by engagement of the cam follower and a cam into another position cutting off fluid flow to arrest movement in said other direction.

24. A mining machine as in claim 23, in which the valve comprises a piston and cylinder assembly, the cylinder having alined ports which form a part of the aforesaid hydraulic system, and the piston having at least one groove capable of being alined with said ports.

25. A mining machine as in claim 24, in which the cam follower is connected to the piston, the connection including a joint to permit off-center movement of the cam follower with respect to the piston.

26. A mining machine as in claim 25, in which said joint is provided with a stop to limit the extent of off-center movement in one direction.

27. A machine as in claim 22, in which the means to initiate action for movement in said other direction and to arrest such movement also includes an electrical system having at least one set of contacts connected to be controlled by the movement in said other direction.

28. A machine as in claim 27, in which the electrical system includes a set of normally closed, time delay opening, contacts connected in parallel with said at least one set of contacts.

29. A machine as in claim 28, in which said at least one set of contacts is connected to be operated by the cam operated mechanism.

30. A machine as in claim 22, in which the means to initiate action for movement in said other direction and to arrest such movement includes an electrical system having a set of contacts connected to be operated by the cam operated mechanism, a set of normally closed, time delay opening, contacts connected in parallel with the first-named set of contacts, a set of normally open contacts, and electrical means connected to close the normally open contacts, the electrical means being in series with the circuit formed by the two first-named sets of contacts.

31. A machine as in claim 22, in which the means to move the instrument in said other direction is hydraulic and the means to initiate action and to arrest such movement includes a hydraulic valve and an electrical system to operate the valve; electrical means to open and close the valve, and control means to complete and interrupt an operating circuit for the electrical means.

32. A machine as in claim 31, the control means including a holding coil and two sets of contacts, the two sets of contacts being connected in parallel with each other and in series with the holding coil.

33. A machine as in claim 32, in which the control means also includes electrical means having a time delay and connected to open one of the two sets of contacts,

the other set of contacts being connected for operation by the cam operated mechanism.

34. In a continuous mining machine having a vein-attacking and disintegrating instrument, means to move said instrument into and to withdraw the instrument from a vein of solid mineral, means to move the instrument about a horizontal axis, and means to move the instrument about a vertical axis, the instrument being movable about the vertical axis through a limited maximum arc, an automatic control system comprising: means to initiate action of the second-named means upon movement of the instrument into the vein a predetermined distance, means to initiate withdrawal action of the first-named means upon movement of the instrument through a predetermined arc about said horizontal axis, means to initiate action to return the instrument about said horizontal axis through substantially said predetermined arc upon completion of withdrawal, means to initiate action to move the instrument about said vertical axis upon completion of withdrawal, the two last-named means being positioned to operate simultaneously, means to arrest movement of the instrument about the vertical axis after the instrument has moved through a fraction of said maximum arc, and means to initiate action of the first-named means to move the instrument into the vein upon completion of return movement of the instrument through said predetermined arc.

35. A mining machine as in claim 34, in which the automatic control system also includes: a plurality of cams and a cam follower, the cam follower having an extended position and a retracted position; an electric power circuit having a set of normally open contacts; and a control circuit for said power circuit including a coil connected to close the set of normally open contacts, and a set of contacts connected in series with said coil and connected to be held open when the cam follower is in its retracted position and closed when the cam follower is in its extended position.

36. A mining machine as in claim 35, in which the control circuit includes a set of normally-closed, time delay-opening contacts in parallel with said cam follower-controlled contacts, and a solenoid to open said normally-closed set of contacts.

37. In a continuous mining machine, a vein-attacking and distintegrating instrument, means to move said instrument through a cycle of a plurality of operations, and an automatic control system comprising means coordinated with movements of said instrument for initiating the successive operations of the cycle including: a plurality of limit means, one for each successive operation and arranged to be actuated by movement of said instrument through its last previous operation; selector means having a given orientation for each operation of said instrument; motor means connected to orient the selector means for the several operations of the instrument; and means connected to be operated by actuation of said limit means for controlling the energization of said motor means.

38. In a continuous mining machine, a vein-attacking and distintegrating instrument, means to move said instrument through a cycle of a plurality of operations, and an automatic control system comprising means coordinated with movements of said instrument for initiating the successive operations of the cycle including: a plurality of limit means, one for each successive operation and arranged to be actuated by movement of said instrument through its last previous operation; selector means having a given orientation for each operation of said instrument, and means connected to be operated by actuation of said limit means and connected to orient the selector means for the several operations of the instrument.

39. A machine as in claim 37, in which the limit means comprise hydraulic pumps in a common circuit;

and the motor means is a hydraulic motor connected in a different circuit.

40. A machine as in claim 39, in which the means connected to be operated by actuation of said limit means includes means to control fluid flow to and from the motor means.

41. A machine as in claim 39 in which said means connected to be operated by actuation of said limit means includes a hydraulic motor connected in said common circuit, said last motor operative to control fluid flow to and from said first motor.

42. A machine as in claim 41, in which the common circuit has a normally fixed volume, whereby operation of any one of the hydraulic pumps serves to operate the second-named hydraulic motor.

43. A mining machine as in claim 37 in which said motor means comprises a rotary electric motor and said means connected to be operated by actuation of said limit means comprising electric motor means, there being means to control the rotary electric motor, and said control means being operated by the electric motor means.

44. A mining machine as in claim 43, in which the control means includes a normally open contactor, the electric motor means including electromagnetic means mechanically connected to close said contactor; and a control circuit for said electromagnetic means, said control circuit including a set of normally closed contacts and a second-named limit switch in parallel therewith.

45. A mining machine as in claim 38, in which the plurality of limit means and the selector means are connected by means which includes a plurality of electric motor means each having a set of normally open contacts and a set of normally closed contacts, a plurality of electromagnetic actuating means for said selector means, and an electric circuit for each last-named means, each such circuit including the normally open contacts of one of the aforesaid electric motor means and the normally closed contacts of another of the aforesaid electric motor means.

46. In a continuous mining machine, a vein-attacking and disintegrating instrument, and supporting and moving means for said instrument including means for moving said instrument successively through like cycles of vein-attacking operations in an upright plane, and means for repositioning said instrument between successive cycles of vein-attacking operations to provide for their successive performance on laterally contiguous portions of an upright face, and controlling means for said supporting and moving means and said repositioning means, including a hydraulic circuit having a slave cylinder and a plurality of master cylinders, the master cylinders constituting limit means actuated by movements of said disintegrating instrument through each operation of said vein-attacking cycle, selector means having a given orientation for each operation, and means connected to and controlled by the slave cylinder to change the orientation of the selector means.

47. In a continuous mining machine having a vein-attacking and disintegrating instrument, means to move said instrument through a cycle of operations including means to move said instrument into and to withdraw the instrument from a vein of solid mineral, means to move the instrument in one direction substantially transverse to the direction of movement into and out of the vein, and means to move the instrument in another direction substantially transverse to the direction of movement into and out of the vein and through a stroke distance which is a multiple of the normal operating stroke distance for

each cycle of operation, an automatic control system comprising: means coordinated with the movement of said instrument into said vein to initiate action of the second-named means upon movement of the instrument into the vein a predetermined distance, means coordinated with the movement of said instrument in said one direction to initiate withdrawal action of the first-named means upon movement of the instrument a predetermined distance in said one direction, means coordinated with the movement of said instrument in a withdrawing direction to initiate action to move the instrument in a direction opposite to said direction upon completion of withdrawal, means to initiate action to move the instrument in said other direction following withdrawal and to arrest such movement after it has progressed through the normal operating stroke distance, said last means including cam operated mechanism, and means coordinated with the movement of said instrument to a position for starting another cycle to initiate action of the first-named means to move the instrument into the vein upon arrival of the instrument in said cycle starting position.

48. In a continuous mining machine having a vein-attacking and disintegrating instrument, means to move said instrument through a cycle of operations including means to move said instrument into and to withdraw the instrument from a vein of solid mineral, means to move the instrument in one direction substantially transverse to the direction of movement into and out of the vein, and means to move the instrument in another direction substantially transverse to the direction of movement into and out of the vein and through a stroke distance which is a multiple of the normal operating stroke distance for each cycle of operation, an automatic control system comprising: means coordinated with the movement of said instrument into said vein to initiate action of the second-named means upon movement of the instrument into the vein a predetermined distance, means coordinated with the movement of said instrument in a withdrawing direction to initiate action to move the instrument into position for starting another cycle, and means coordinated with the movement of said instrument into position for starting another cycle to initiate action of the first-named means to move the instrument into the vein upon arrival of the instrument in said cycle starting position.

49. A machine as in claim 48 in which said means for initiating movement of said instrument into position for starting another cycle includes means to initiate movement of said instrument in a direction opposite to said one direction and means to initiate action to move the instrument in said other direction following withdrawal and to arrest such movement after it has progressed through the normal operating stroke distance, said last means including cam operated mechanism.
